UNITED STATES PATENT OFFICE.

PETER C. BROSIUS, OF CHICAGO, ILLINOIS.

CLEAT.

1,100,170.

Specification of Letters Patent. Patented June 16, 1914.

Application filed December 23, 1913. Serial No. 808,355.

To all whom it may concern:

Be it known that I, PETER C. BROSIUS, a citizen of the United States, residing at Chicago, in the county of Cook and State of Illinois, have invented certain new and useful Improvements in Cleats; and I do hereby declare the following to be a full, clear, and exact description of the invention, such as will enable others skilled in the art to 10 which it appertains to make and use the same.

This invention relates to new and useful improvements in cleats and has for its principal object the provision of a cleat which is 15 to be used on railway platforms and in connection with the loading and unloading of cars to hold the run board in place.

Another object of the invention is the provision of a device which will hold the lower 20 edge of the run board and prevent the same from slipping or becoming displaced in any way.

A further object of the invention is the provision of a movable cleat which may be 25 placed at the desired point for use and when advisable may be removed and replaced without involving any great amount of labor or expending much time in the operation.

A still further object of the invention is to 30 provide a device of the above character which will materially assist in running a wheel barrow or other transporting device over the edge of the run board as the cleat is provided with a beveled end.

With the above and other objects in view 35 the invention consists in the novel combination and arrangement of parts which will be fully set forth in the following specification and accompanying drawings, in which—

Figure 1 is a detail perspective view of a 40 portion of the platform and a portion of a car, showing the cleat and run board as they would appear when in position, Fig. 2 is a longitudinal sectional view of the cleat 45 showing the same on an enlarged scale, to clearly set forth the details, and Fig. 3 is an enlarged detail perspective view of the bottom of the cleat to clearly set out the teeth by which it is secured to the platform.

Referring now to the drawings by characters of reference the numeral 1 designates a 50 railway car standing beside a platform designated generally by the numeral 2.

The usual run board indicated by the 55 numeral 3 is placed on the door sill of the car and is so arranged as to form a gradual in-

cline over which the loading and unloading trucks or other devices may pass. The cleat which co-operates with the lower edge of the run board to hold said board in place is indicated generally by the numeral 4, and is illustrated in detail in Figs. 2 and 3. The cleat above referred to, which is indicated by the numeral 4, is formed of a suitable body portion 5, which is provided with two sets of angularly projecting spurs 6 and 7, 60 which are arranged in parallel relation and formed integral with the body portion near its opposite end. These spurs preferably extend at an angle to a perpendicular taken 65 transversely through the body portion, as clearly illustrated in Fig. 2. The rear end of the body portion 5 is beveled as clearly 70 illustrated at 8 to permit the wheels of the trucks or other transporting means to more 75 easily ride over the end of the run board 3. The opposite end of the body portion 5 is preferably recessed on its under side, as at 9, the wall of said recess being beveled, as 80 clearly shown in Fig. 2 and this recess is so arranged as to form the shoulder 10 against which the edge of the run board 3 passes when the device is in use.

It will be clearly seen from the foregoing 85 that when it is desired to make use of the device the car is run along the tracks at the desired point, and the cleat placed in front of the door of the car and driven firmly in place. The run board is then placed in position, with the ends thereof abutting the 90 shoulder 10 on the cleat and it will be apparent that owing to the beveled wall of the recess the same will permit of the proper adjustment of the angle at which the run board is placed without interfering with the 95 cleat. It will then be evident that the run board will be held from slipping out of place and the material loaded or unloaded from the car, and the amount of danger accompanying such a process will be minimized. 100

While in the foregoing I have shown and described the preferred embodiment of the invention it is to be understood that I may make such changes in the arrangement and combination of parts as fall within the scope 105 of the appended claims.

What is claimed is:

1. A device of the character described comprising a body portion, a plurality of spurs formed on the under side of said body 110 portion, and extending angularly with relation thereto, said body portion being beveled

at one end and recessed at the other end to form a shoulder, which is adapted to co-operate with the run board of a freight car, whereby the same will be prevented from 5 becoming displaced.

2. A device of the character described comprising a body portion, said body portion having a recess in one end, said recess forming a shoulder, the opposite end of said 10 body portion being beveled on the opposite side, and a plurality of spurs formed in the bottom of said body portion and adapted to enter the woodwork of a railroad platform when the device is in use.

3. A device of the character described comprising a body portion, said body por-

tion being provided at one end with a recess having one wall thereof extending at an angle to the body portion, and a shoulder formed by the other wall, the opposite end 20 of said body portion being beveled, and a plurality of spurs extending in parallel relation to each other at each end of the body portion, whereby the same may be attached to a railroad platform when it is in use. 25

In testimony whereof I affix my signature in presence of two witnesses.

PETER C. BROSIUS.
